UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FASTENER.

1,126,973.

Specification of Letters Patent.

Patented Feb. 2, 1915.

Application filed January 24, 1914. Serial No. 814,064.

To all whom it may concern:

Be it known that I, FRANZ A. FULLER, a citizen of the United States, residing in the city of Newark, in the county of Essex and 5 State of New Jersey, have invented certain new and useful Improvements in Bag-Fasteners, of which the following is a full, clear, and exact description, such as will enable others skilled in the art to which it pertains, 10 to make, construct, and use the same, reference being had to the accompanying drawings, and to numerals of reference marked thereon, forming a part of this specification.

This invention relates to certain improvements in fasteners, and particularly to fasteners for satchels, bags, pocket-books, and the like, and has for its object, the arrangement of an improved structure designed to co-act with the ordinary fastener of a 20 satchel for preventing an accidental loosening or unfastening of the same.

A further object of the invention is to provide a pivotally mounted auxiliary locking device in connection with a bag frame 25 having the ordinary lift-lock or overlapping locking knobs, so that the auxiliary locking device may embrace the ordinary fastener for preventing opening thereof.

In its preferred embodiment, my improved device includes a pivoted member 30 carried by one of the jaws, which when swung in one direction, will positively prevent the lock from opening; but when swung in the opposite direction, will permit the free opening of the ordinary fastener.

In carrying out my invention, I make use of the preferred structures illustrated in the accompanying drawings, in which—

Figures 1 and 2 represent front elevations 40 of a bag frame having applied thereto my improved bag fastener, in Fig. 1, part of the frame and post being broken away to illustrate the manner in which the several parts are connected. Fig. 3 represents a 45 plan view of the same, with the handle securing loop swung into a horizontal position; and Fig. 4 represents a transverse section taken on lines $x-x$ of Fig. 1, and looking in the direction indicated by the arrow.

Similar numerals of reference refer to like parts throughout the specification and drawings.

In the first form illustrated, my invention is applied to any ordinary or desired form 55 of frame, consisting of two hinged members

1 and 2. Near the middle portion of the frame member 1, I secure the fastener 3 of the lift-lock type, in any convenient or desired manner, which is operatively connected with the frame member 2 by snapping 60 or forcing the edge of the fastener over the usual projection (not shown) upon the frame member 2 in the well-known manner. In the second form illustrated, my invention is applied to a frame provided with locking 65 knobs 5 and 6, which interlock in the usual manner.

7—7 represent apertured studs of any convenient form, secured to the frame member 1 by means of an integral reduced portion 8 70 inserted through apertures in the bag frame member 1 and riveted over in any suitable or convenient manner.

9 represents a locking element pivotally connected to the apertured studs 7 by means 75 of integral trunnions 10 formed thereon.

11 indicates a stud which is fastened to the frame member 2 in any convenient or desired manner, designed to engage with a recess 16 formed in the locking element 9 80 and have locking engagement therewith, as shown. This locking element is made from a single piece of suitable material, formed with two arms 12 from which the trunnions extend, and by means of which it is pivotally connected to the studs 7. These arms 12 are provided with offset portions 13 which engage with the lift-lock 3, so that when the locking element is in locked position it will be impossible to disengage the 90 lift-lock 3 from the usual projection on the frame member 2. The lower portion 14 of the locking element is preferably curved outwardly to provide convenient means for manipulating the lock, in order to disengage the same from the stud 11.

15 represents a loop or handle securing means, the ends of which are pivotally secured in the apertured studs 7—7, for the reception of that type of handle known as 100 the flat or strap handle.

The invention is not limited to the exact embodiment shown, but may be modified in various ways in the scope of the following claims.

I claim:

1. In combination, two members movable relatively to each other, a fastener secured to one of said members and holding said frame members together, posts secured on 110

one frame member, and a locking element, comprising a yoke pivotally located in said posts, said yoke being designed to embrace and overlie the fastener secured on the first-named member and operated independently from said fastener.

2. In combination, two members movable relatively to each other, a fastener secured to one of said members and holding said frame members together, apertured posts secured to one frame member, and a locking element, comprising a yoke provided with trunnions which are pivotally located in said posts, said yoke being provided with a recess to engage a knob on the other frame member having locking engagement therewith, said yoke being further adapted to embrace and overlie the fastener secured on the first-named member and operated independently from said fastener.

3. In combination, two members movable

relatively to each other, a fastener secured to one of said members and holding said frame members together, apertured posts secured to one frame member, strap-supporting means pivotally secured to said posts, and a locking element, comprising a yoke provided with trunnions which are pivotally located in said posts, said yoke being provided with a recess to engage a knob on the other frame member having locking engagement therewith, said yoke being further adapted to embrace and overlie the fastener secured on the first-named member and operated independently from said fastener.

This specification signed and witnessed this 22nd day of January, 1914.

FRANZ A. FULLER.
